[57] CLAIM

The ornamental design for an integrated circuit test clip, as shown and described.

DESCRIPTION

FIG. 1 is a perspective view of an integrated circuit test clip, showing our new design;

FIG. 2 is a side elevation view thereof, the opposite side being substantially identical to that shown;

FIG. 3 is a side elevation view thereof, orthogonal to the view shown in FIG. 2, the opposite side being substantially identical to that shown;

FIG. 4 is a top plan view thereof; and

FIG. 5 is a bottom plan view thereof.

The cables have been broken away in FIGS. 1-4 to indicate indeterminate length.

FIG. 2
